CLAIM

The ornamental design for a pulp molding die as shown and described.

DESCRIPTION

FIG. 1 is a top perspective view of a pulp molding die showing our new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a cross-sectional view taken along line 9-9 of FIG. 3;

FIG. 10 is a cross-sectional view taken along line 10-10 of FIG. 3;

FIG. 11 is an enlarged view of the circled area 11 of FIG. 9; and,

FIG. 12 is an enlarged view of the circled area 12 of FIG. 10. The evenly dashed broken lines depict portions of the pulp molding die in which the design is embodied that form no part of the claimed design.

The dash-dotted broken line circles and lead lines in FIGS. 9-12 depict the boundaries of the enlarged views and form no part of the claimed design.

The remaining dash-dotted broken lines in FIGS. 9 and 11 define bounds of the claimed design only and form no part thereof.
